UNITED STATES PATENT OFFICE

148,932

DESIGN FOR A CANDLE HOLDER

David Kaplan, New York, N. Y.

Application May 8, 1946, Serial No. 129,456

Term of patent 3½ years

(Cl. D48—2)

To all whom it may concern:

Be it known that I, David Kaplan, a citizen of the United States of America, residing at New York, in the county of New York and State of New York, have invented a new, original, and ornamental Design for a Candle Holder, of which the following is a specification, reference being had to the accompanying drawing, forming part thereof.

I claim:

The ornamental design for a candle holder, as shown.

DAVID KAPLAN.
